NECKTIE RETAINER

Ivan R. Lang, Omaha, Nebr.

Application May 7, 1948, Serial No. 25,699

3 Claims. (CL 24—49)

1

This invention relates to a retainer member for a necktie and more particularly to a retainer member for a four-in-hand necktie that is tied in a knot with the retainer entered into the knot of the tie and secured to front and rear scarf portions of the necktie to prevent slippage and disarrangement of the knot and disarrangement of the front and rear scarf portions and is further an improvement over applicant's co-pending application Serial No. 743,582, filed April 24, 1947.

The four-in-hand necktie has a tendency to slip when tied in a knot which allows the loop of the tie around the neck to enlarge and let the knot sag and slip so that by the end of the day, a wearer has an unkept look. Further, if the knot becomes loosened the front and back scarf portions of the tie will become disarranged and give a sloppy appearance to a wearer. It is with the problem of keeping a necktie neat and trim on a wearer and providing one structure that can be used with all sizes of neckties that the present invention is concerned.

It is an object of the invention, among others, to provide a necktie retainer that will hold the knot of the necktie from slipping or being displaced when on a wearer regardless of the size of the necktie knot and to hold the front and rear scarf portions from becoming disarranged; a necktie retainer that will function with any size necktie and only one structure is necessary to care for a wide variety of sizes in necktie knots; a necktie retainer that is simple in design hence simple and economical to construct; a necktie retainer that requires no special skill on the part of a necktie wearer to attach within the knot of a necktie and to the scarf portions; a necktie retainer that has two anchor points when mounted hence no chance to slip when mounted on a necktie; and a necktie retainer that will sell at an economical price well within the range of all necktie wearers.

With the foregoing and other objects in view, the invention will be more fully described here-with and will be particularly pointed out in the claims appended hereto.

In the drawings, where like symbols refer to like or corresponding parts throughout the several views:

Figure 1 is an elevational view of the necktie retainer.

Figure 2 is a rear view of a four-in-hand necktie tied in a knot with the necktie retainer in place and the knot illustrated as being of large size.

Figure 3 is a rear view of a four-in-hand neck-

2

tie tied in a knot with the necktie retainer in place and the knot illustrated as being of a smaller size than the knot of Figure 2.

Figure 4 is a sectional view, taken on the line 4—4 of Figure 2 passing through the knot and scarf portions of the necktie and showing the necktie placed in a collar.

The necktie retainer is represented generally at 1 with an upper portion 2 and a prong 3 on the end of a shank 4 with the structure being made from a single piece of wire. The upper portion 2 differs from the previously filed structure in that the wire is bent into the upper portion 2 in the shape of a diamond instead of a triangle. The diamond shaped upper portion has the advantage that only one retainer need be supplied whether the necktie is tied with a front scarf overlapped from the right or left hand. In Figure 2 the front scarf 5 of the necktie is tied from the left hand side while in Figure 3 the front scarf is tied from the right hand side and it will be noted that the same retainer 1 is employed in each instance.

In forming the diamond shaped upper portion 2, the wire is bent outwardly at the point 6 to form the side 7 of the upper portion 2, which point 6 is also the top of the shank 4 and the lower apex of the diamond shaped upper portion 2. The side 8 is then formed by the wire being bent inwardly and extending upwardly. The wire is then bent downwardly and outwardly to form the side 9 with the diamond shaped upper portion 2 being closed by the side 10 extending downwardly and inwardly with one end 11 of the wire wrapped around the shank 4 at the point 6. The diamond upper portion 2 may be made of a length and a width that will care for a small necktie or one that ties into a knot having a relatively small length. The scarf portions of neckties have different widths and are made of materials of different thickness. The length of knot will vary with the width of scarf portions of the necktie, hence the length of the diamond shaped upper portion 2 is selected to care in general for neckties of a narrow width.

On the lower end of shank 4 is a triangular portion 12 formed by the wire being bent into shape to form a pressure point for a finger 13 to force the prong 3 into a rear scarf portion 14 of the necktie. It can therefore be seen that prong 3 is one end of the principal or longer wire extending at right angles to the plane of loop 2 and the other end 11 is wrapped around the top of shank 4 to close the loop 2.

A hook 15 extends outwardly from the point 6

and has an eye portion 16 fitting around the shank 4, with the hook 15 movable up and down on the shank 4 with relation to the upper portion 2. The hook 15 is perpendicular to the plane of the upper portion 2 and extends in the opposite direction to the prong 3. The hook 15 is made of a separate piece of wire which is bent to form the eye 16 with the wire then extending upwardly to form a straight portion 17 ending in a loop 17a. The portion 17 connects with a resilient means 18, which may be any type extensible member, with a coil spring disclosed as one example of a resilient member that may be used. The top of the coil spring 18 connects to the retainer member at the top of the upper portion 2 in an eye 19 formed at this point. The hook 15 may be moved downwardly on the shank 4, thus extending coil spring 18 to place the spring under tension. When the force moving hook 15 downward is removed the coil spring 18 will return the hook 15 to its original position in contact with the end 11 of the wire.

Neckties of the four-in-hand type may be tied by two different methods. The first as represented in Figure 2, the wearer starts with front scarf 5 on his left in tying the necktie and the knot ties into the form shown in Figure 2. Where the wearer starts with the front scarf 5 on the right, the knot ties into form shown in Figure 3. In the previous embodiment, two separate types of retainers were needed to care for the different methods of tying the knots, but as can be seen by the present type retainer 1, the diamond shaped upper portion 2 allows the present retainer 1 to be used regardless of how the knot is tied. The upper portion 2 fits between the folds of the necktie forming the knot as shown in Figures 2 and 3 and is entered into the knot until the eye 19 and the upper portion 2 becomes wedged in the top of the knot. To provide a first anchoring point, the hook 15 is provided to contact the outer edge of the portion of the necktie forming the bottom of the knot. The hook 15 provides a second anchoring point which with the top portion 2 holds the retainer in place within the knot against sidewise motion. The hook 15 can thus be moved for different length knots so that one type retainer can be used for different type and width neckties.

The retainer 1 is made of a spring wire and No. 12 piano wire has been used successfully. The side apexes of the diamond shaped upper portion 2 form contact points in the knot which prevent sidewise motion of the upper portion 2 within the knot.

After the necktie has been tied around the neck of a wearer, and the knot formed, the rear scarf 14 is pulled through the knot of the necktie, pulling the necktie tight around the neck and the knot firm against the collar. The necktie is now ready to receive the necktie retainer 1 hence rear scarf 14 and front scarf 5 are lifted upwardly and outwardly sufficiently to allow the wearer to get to the back of the knot of the necktie. The upper portion 2 is entered into the knot between the rear fold of the knot and rear scarf 14 forming the knot and pushed upwardly until the portion 19 wedges in the top of the knot. The hook 15 contacts the lower portion of one of the folds making up the knot and if the knot is longer than the upper portion 2, the spring 18 is placed under tension by the hook 15 being moved downwardly on the shank 4. The thumb or any finger 13 then contacts triangular portion 12 and forces the prong 3 inwardly into the rear scarf

14. The contact portion 12 is of substantial size so that the force exerted by the finger is spread over a substantial area and thus prevents injury to a finger 13 exerting the force. The sharpened 5 prong 3 is made to pierce the rear scarf 14 of the necktie which secures and anchors the lower end of the retainer 1, in place to provide a third 10 reaction point. With the retainer 1 in place, the rear scarf 14 is prevented from slipping backwardly through the knot and the necktie remains 15 tight about the neck and the knot firm against the collar in neat and proper position. The point 3 is bent downwardly slightly to prevent inadvertent removal of the point 3 from the rear scarf 14.

The upper portion 2 is wedged and anchored as to sidewise movement and the knot cannot break or bend at either side since the upper portion 2 acts as a reenforcement within the knot 20 to prevent bending to throw the scarf portion 5 and 14 to either side which would improperly space the scarf portions 5 and 14 with relation to collar, shirt and coat. The big difficulty with most neckties is that the rear scarf portion 14 has 25 a tendency to slip through the knot with the flexing of the muscles of the neck. This enlarges the loop around the neck and allows the necktie knot to sag within the collar giving a wearer an extremely sloppy appearance. The retainer 1 is anchored by prong 3 which is bent to block 1 from pulling out of the rear scarf 14, hence there can be no slipping of the rear scarf 14 through the knot. The front and rear scarf portions 5 and 14 are held in alignment when the retainer 30 1 is in place by the upper portion 2 wedged within the knot forming a first anchoring point; the hook 15 forming a second anchoring point and the prong 3 forming a third anchoring point so the rear scarf 14 cannot work around to the side or in front of the front scarf 5.

It is noted that not all neckties are the same size hence some neckties will tie into smaller knots than others. The present retainer 1 can 45 be used with any sized knot since the hook 15 is movable. The present structure therefore presents a standard retainer usable with ties where the front scarf is tied either from the right or left and where the ties vary in size and thickness to give varying length knots when tied.

50 It will be understood that the invention has been described for purposes of illustration and explanation and that changes and variations are possible without departing from the scope of the invention; all such modifications and changes 55 are intended to be included in the appended claims.

I claim:

1. In a knotted four-in-hand tie retainer, a 60 wire frame means having a diamond shape portion designed to rest within the knot of a knotted four-in-hand tie and a downwardly extending shaft portion designed to extend below the knot of the tie to which the retainer is designed to be applied, a hook member slidably mounted 65 on said downwardly extending shaft portion designed to engage the under bottom edge of the knot of the tie to which the retainer is designed to be applied, a coil spring having one end secured to the top of the diamond portion of said wire frame and its other end secured to said hook member for yieldingly holding said hook member in a direction toward said diamond shape portion of said frame means, and a pointed projection on the lower end portion of said down- 70 75

wardly extending shaft designed to engage the scarf of the tie to which the retainer is designed to be applied.

2. In a knotted four-in-hand tie retainer, a wire frame means having a diamond shape portion designed to rest within the knot of a knotted four-in-hand tie and a downwardly extending shaft portion designed to extend below the knot of the tie to which the retainer is designed to be applied, a hook member slidably mounted on said downwardly extending shaft portion designed to engage the under bottom edge of the knot of the tie to which the retainer is designed to be applied, a coil spring having one end secured to the top of the diamond portion of said wire frame and its other end secured to said hook member for yieldingly holding said hook member in a direction toward said diamond shape portion of said frame means, an eye stop formed on the lower end portion of said downwardly extending shaft, and a pointed projection on the lower end portion of said downwardly extending shaft designed to engage the scarf of the tie to which the retainer is designed to be applied.

3. In a knotted four-in-hand tie retainer, a wire frame means having a diamond shape portion designed to rest within the knot of a knotted four-in-hand tie and a downwardly extending shaft portion designed to extend below the knot of the tie to which the retainer is designed to be

applied, a hook member slidably mounted on said downwardly extending shaft portion designed to engage the under bottom edge of the knot of the tie to which the retainer is designed to be applied, a coil spring having one end secured to the top of the diamond portion of said wire frame and its other end secured to said hook member for yieldingly holding said hook member in a direction toward said diamond shape portion of said frame means, an eye stop formed on the lower end portion of said downwardly extending shaft, and a pointed projection on the lower end portion of said downwardly extending shaft designed to engage the scarf of the tie to which the retainer is designed to be applied; said hook member and said pointed projection extending in opposite directions.
